Primary Examiner — Michael A. Pratt(74) *Attorney, Agent, or Firm* — BURR & FORMAN LLP(57) **CLAIM**

The ornamental design for an extractor socket, as shown and described.

DESCRIPTION

FIG. 1 is a perspective view of an extractor socket in accordance with a first embodiment of the present invention; FIG. 2 is a top view of the extractor socket of FIG. 1; FIG. 3 is a bottom view of the extractor socket of FIG. 1; FIG. 4 is a side view of the extractor socket of FIG. 1; FIG. 5 is a perspective view of an extractor socket in accordance with a second embodiment of the present invention;

FIG. 6 is a top view of the extractor socket of FIG. 5; FIG. 7 is a bottom view of the extractor socket of FIG. 5; and, FIG. 8 is a side view of the extractor socket view of FIG. 5. The broken lines of FIGS. 1-8 form no part of the claimed design.
